Pfaff and Kendall, Newark, N.J., a corporation of New
Jersey

Filed July 15, 1964, Ser. No. 80,884

Term of patent 14 years

(Cl. D54—1)

FIG. 1

FIG. 2

FIG. 3

FIG. 4

FIG. 5

FIG. 6

FIG. 1 is a side elevational view of a bracket for posts, showing my new design;

FIG. 2 is a top plan view;

FIG. 3 is a side elevation of the bracket member at the right of FIG. 1;

FIG. 4 is a side elevation of the bracket member at the left of FIG. 1.

FIG. 5 is a top plan view thereof, and

FIG. 6 is an end elevation thereof.

The broken line showing of a post and arm in FIGS. 1 and 2 is for illustrative purposes only. The dominant feature of my design resides in the portions shown in full lines.

I claim:

The ornamental design for a bracket for posts, as shown and described.
